WRENCH

Harold C. Reynolds, Athens, Pa., assignor to Ingersoll-Rand Company, New York, N. Y., a corporation of New Jersey

Application August 31, 1944, Serial No. 552,025

2 Claims. (Cl. 192—150)

This invention relates to wrenches, and particularly to wrenches driven by fluid actuated motors.

One object of the invention is to provide a construction for a wrench which will develop torque limited to a predetermined maximum value.

Another object of the invention is to provide an adjustment by which the maximum torque of a motor driven wrench may be varied as desired.

Another object of the invention is to provide a relatively simple and inexpensive construction for a motor driven wrench which is adapted to automatically stop the motor when a predetermined torque is reached.

Other objects of the invention will be in part obvious and in part pointed out hereinafter.

In the drawing in which similar reference characters refer to similar parts,

Fig. 1 is a side view of a wrench constructed in accordance with the practice of the invention.

Fig. 2 is a cross sectional view of the front end of the tool taken along the line 2—2 of Fig. 1 looking in the direction of the arrows.

Fig. 3 is a horizontal longitudinal section of the forward end of the tool taken along the line 3—3 of Fig. 1 looking in the direction of the arrows.

Fig. 4 is a cross section through the spring compressing adjustment taken at the line 4—4 of Fig. 3.

Fig. 5 is a cross sectional view through the throttle valve and casing of the tool taken along the line 5—5 of Fig. 1 looking in the direction of the arrows, portions of the casing being shown in section, and

Fig. 6 is a detail view of the stem of the throttle valve and its operating mechanism taken along the line 6—6 of Fig. 5 looking in the direction of the arrows, portions of the casing being shown in section, and

Fig. 7 is a cross sectional view through the motor and the throttle valve actuating means taken along the line 7—7 of Fig. 1 looking in the direction of the arrows.

Fig. 1 is an external view of the wrench with portions of the interior mechanism shown in broken lines and shows the working parts of the tool to be inclosed in a casing comprising a motor housing 10, a gear casing 11, and a casing 12 for the shaft to be described hereinafter. Motive power for the tool is provided by vane-type motor having a rotor 14 provided with the conventional vanes 15. For controlling the flow of motive fluid to the motor there is provided a throttle valve 16 housed in the backhead 117 of the motor which controls the flow of motive fluid from an inlet port 17 to a supply port 18 leading to the motor. To

indicate more clearly the connection with a suitable supply of motive fluid (not shown) a nipple 19 and a shut off valve 20 are shown coupled to the backhead 117 at the port 17.

5 The rotor 14 of the motor is provided with a shaft 21 extending into the gearing box 11 and is adapted to drive through suitable planetary gearing 22 a shaft 23. Within the shaft housing 12 is disposed a longitudinally extending shaft 24 journaled on an antifriction bearing 25 in a bore 26 of the housing 12 and on a second antifriction bearing 27 provided adjacent the outer end of the shaft 24 and slidably mounted in a bore 28 in the casing 12.

10 Shaft 24 is adapted to slide with its bearings in the bores 26 and 28 but is opposed in such motion by the compressive force of a spring 29 arranged about the shaft 24 and having a forward abutment 30 shaped somewhat like a cup and bearing against the race of the bearing 25. The rear end of the spring 29 is disposed within a rearward abutment 31 slidable in the bore 26 of the housing 12.

15 The shaft 24 is adapted to be driven by shaft 23 and to this end a coupling member 32 is provided which is screwed into the end of the shaft 23 as shown at 33 and is provided with a bore 34 to receive the end of shaft 24. Relative rotation between the two shafts is prevented by ball 35 lying in a groove 36 in the shaft 24 and a complementary groove 37 provided in the bore 34 of the coupling member 32. Ball 35 is adapted to permit relative longitudinal movement of the coupling member 32 and the shaft 24.

20 25 Compression of the spring 29 is adjustable by means for varying the position of the abutment 31 and to this end there are provided a plurality of pins 38 (Fig. 4) extending into bores 39 of the abutment 31 and through the wall of the casing 12 at suitable longitudinal slots 40 to engage a threaded ring 41 encircling the casing 12. Longitudinal motion of the ring 41 is accomplished by a nut 42 threaded to receive the ring 41 and having a rearward face 43 abutting a coupling 44 forming part of casing 12 and threaded into it as shown at 45. Coupling 44 provides a means of threadingly attaching the casing 12 to the gear housing 11.

25 30 35 Shaft 24 is adapted to drive the socket receiving spindle 48 through suitable worm gearing comprising the worm 49, formed integrally with the shaft 24, and the worm wheel 50 fitting the spindle 48 at a hexagonal portion 51. Spindle 48 is suitably housed within an offset portion 52 of the casing 12 having a cap 53 supporting a

bearing 54 for one end of the spindle 48 and a sleeve 55 forming a bearing adjacent the socket receiving end of the spindle.

For actuating the throttle valve 16 there is provided a mechanism adapted to be actuated both manually and automatically through the longitudinal motion of the shaft 24. This mechanism comprises a shaft 56 exterior to the tool casing and substantially parallel to the axis of the tool having a bearing in a bracket 57 at the forward end of the casing 12 and in a band 58 suitably clamped to the back head 17 by means of a contracting bolt 59. Shaft 56 is provided with an arm 60 normally contacting the end of the valve 16 which it is adapted to depress against the biasing spring 61. Shaft 56 carries a hand-operated lever 62 for turning the shaft and operating the throttle valve 16. Shaft 56 is movable longitudinally against the pressure of a biasing spring 63 and when moved rearwardly is adapted to disengage the end of the throttle valve 16 permitting it to close.

When moved to the rear so as to disengage the throttle valve the spring 64 is adapted to raise the lever 62 to its normal outwardly extending position. Longitudinal motion of the shaft 56 is affected by the abutment 30. For this purpose the bracket 57 is attached to the abutment 30 by means of a screw 65 passing through the casing 12 at the slot 66 there being a sleeve bearing 67 provided on the screw 65 to engage the walls of the slot 66.

As indicated in Fig. 1, a socket 70 may be provided on the spindle 48 to engage a suitable nut 71 for tightening or loosening as the case may be.

In operation, the motor within the casing 10 is actuated by depressing the lever 62 which by means of the arm 60 depresses the throttle valve 16 admitting motive fluid through the supply port 18 to the motor. The torque of the motor is transmitted through the shaft 21 and gearing 22 and shaft 23 to the shaft 24 and thence through the worm gears 49 and 50 to the spindle 48. Resistance of the nut 71 to rotation of the spindle 48 causes end thrust in the shaft 24 in the direction toward the right, as shown in the figures. This end thrust is transmitted through flange 72 to the bearing 26 and the forward abutment 30 tending to compress the spring 29. As the end thrust becomes greater the compressive force of the spring 29 is overcome, pushing the abutment 30 rearwardly and through the bracket 57 also pushing the shaft 56 rearwardly. At a predetermined torque of the shaft 24 the degree of longitudinal motion of the shaft 24 is such as to cause the bracket 57 to push the shaft 56 and its arm 60 sufficiently far back to disengage the throttle valve 16 whereupon the valve closes un-

der the influence of its spring 61 and shuts down the motor.

Upon stoppage of the motor as described and removal of the wrench from the nut 71 spring 29 restores the bracket 57 to its normal forward position. The lever 62 having been released, the biasing spring 63 pushes shaft 56 forward to bring the arm 60 to register with the stem of valve 16 for subsequent operation.

The value of the torque required to overcome the compression of the spring 29 is determined and is adjustable by means of the nut 62 which advances or retracts the ring 41 as desired and compresses the spring 29 accordingly by the corresponding movement of the abutment 30. Suitable adjustment of the nut 62 may be had by applying a torque wrench of any well-known type to the spindle 48 and applying the desired torque to it while adjustment of the nut 62 is made.

Thus, by the above described construction are accomplished the objects hereinbefore referred to.

I claim:

1. A wrench including a casing, a motor within the casing, a shaft in said casing adapted to be driven by said motor and to be moved endwise of said motor by the torque thereof, a throttle valve for the motor, operative connections between said shaft and said valve to release the valve upon said endwise movement, a spring positioned about said shaft and adapted to resist said endwise movement and means to adjust the compression of said spring including an abutment member within the casing, members extending through the casing to engage the abutment and to prevent rotation thereof, a threaded ring engaging the outer ends of said members, and an adjusting nut exteriorly of the casing for said ring abutting the casing.

2. A wrench including a casing, a motor within the casing, a shaft in said casing adapted to be driven by said motor and to be moved endwise by the torque thereof, a throttle valve for the motor, manually operable means for said valve, operative connections between said shaft and said manually operated means to disengage said valve upon said endwise movement, a spring about said shaft and adapted to resist said endwise movement and means to adjust the compression of said spring including an abutment member within the casing, members extending through the casing to engage the abutment and to prevent rotation thereof, a threaded ring engaging the outer ends of said members, and an adjusting nut for said ring rotatable on the exterior of and abutting the casing.

HAROLD C. REYNOLDS.
